FREDERICK S. McCULLOUGH, OF EDGEWOOD, PENNSYLVANIA

CIRCUITS FOR THERMIONIC TUBES

Application filed August 25, 1925. Serial No. 52,307.

This invention is for an improvement in a circuit for thermionic tubes, particularly tubes of the type having an indirectly heated cathode, and is especially applicable to a radio receiving circuit.

5 Certain forms of tubes have been designed having a cathode which is heated by means of a suitable heater adapted to be included in an alternating current circuit. Such tubes, as usually constructed, have in addition to the usual plate and grid, a cathode in the form of a cylinder fitted over a porcelain rod. Within this rod, is a resistance wire adapted to be coupled in an alternating current circuit.

15 Since the cathode is not energized by the passage of current therethrough, as is the cathode of the more common type of tube which has the cathode in the form of a filament, it is termed an equi-potential cathode, 20 and there is in the normal operation of such tubes, as now used, no means for obtaining a potential gradient along the cathode. Such a tube, furthermore, is not capable of delicate temperature variations, and it is not convenient to control the temperature of the cathode. 25 It is accordingly quite difficult to control the oscillations of the tube, particularly as a detector.

The present invention has for its object to 30 provide in combination with a tube of this character, means for establishing a potential difference between different parts of the cathode and then varying this potential on different parts of the cathode as required, to control the oscillations of the tube.

35 A further important object of the invention is to provide means in the circuit for eliminating from the circuit either partly or entirely, the hum which might otherwise exist by 40 reason of the use of alternating current for energizing the cathode.

The invention may be readily understood by reference to the accompanying drawing which shows a tube of the type referred to 45 coupled into a circuit embodying my invention. It will be understood that the figure shown is more or less diagrammatic, and that the invention is not restricted to the particular construction of the tube or the arrangement of the circuits therein illustrated.

In the drawing, 5 designates a suitable vessel within which is a plate or anode 6. Within the plate is a grid 7 of any preferred construction. Within the grid and out of contact therewith, is the cathode. The cathode as 55 herein illustrated, comprises two convergently arranged refractory rods 8 through which passes a V-shaped resistance wire 9. Fitted over each rod 8 is a cylindrical shell 10. These shells form the cathode of the tube. They are 60 preferably out of contact with each other, and are either of a substance having a high electron emissivity, or they are coated with a suitable substance for giving the desired emission. The opposite ends of the V-shaped 65 resistance wire 9 may be coupled in circuit with a suitable source of alternating current as indicated at 11. In practice, this alternating current may be derived from a house lighting circuit stepped down by a suitable 70 transformer, as indicated. Leading through the tube, at a suitable point, is a conductor 6^a which connects the plate with a suitable external circuit. This circuit may include the translating device T, which may be a telephone or any other suitable current responsive device and a source of plate current, indicated at B. A wire 7^a leads from the grid 75 of the tube. One of the cathode members 10 is connected with a lead-in wire 12, and the 80 other one with a lead-in wire 13.

Wire 13 may be connected to the plate and grid circuits in a suitable manner, this point of connection being indicated at 16. Interposed between point 16 and the cathode of the 85 tube, is a suitable reactance or impedance designated 14. This may be shunted by a suitable radio frequency by-pass, as for instance, a condenser 14^a. Between the point 16 and the reactance 14 there is preferably a resistance 90 17 that connects wires 12 and 13. This is preferably a variable resistance as shown. It may, for example, have a maximum resistance of 25,000 ohms and this may be varied 95 as desired. The variable contact for the resistance is indicated at 17^a and is connected with wire 12. If desired, a second reactance may be included in wire 12 between the contact 17^a and the portion of the cathode with which wire 12 connects, this impedance 100

being shown in dotted lines and being designated 15. It, too, may be shunted by a radio frequency by-pass as indicated in dotted lines. Under some circumstances it might be 5 desirable to provide additional condensers as indicated in dotted lines at 21.

The grid circuit may be of any well known character. I have shown the circuit as a 10 detector circuit with an inductance 20 and a 15 grid leak and grid condenser diagrammatically indicated at 19.

In the operation of the tube, the resistance wire 9 is heated by an alternating current passing therethrough. This in turn heats the 15 porcelain rods 8 and the cathode members 10. When the cathodes are heated, there will be 20 a current flow between the plate and the cathodes as in any thermionic tube. By adjustment of resistance 17, it is possible to restrict 25 the current flow between one of the cathodes and the plate, so as to create a potential difference between the two cathode members.

By proper adjustment of this potential difference it is possible to control the oscillations 25 of the tube. At the same time the impedance 14 between the cathode and the resistance 17 functions to retard alternating current impulses set up in the circuit by reason of the use of an alternating current in the heater 30 wire. The by-pass condenser 14^a will permit radio frequency oscillations to pass the impedance but the lower alternating current frequencies will be substantially eliminated.

The capacity and arrangement of the condensers and the nature of the impedances 35 may be adjusted and varied according to the characteristics of the circuit in which the tube is used and according to the manner in which it is desired that the tube shall function. It 40 will accordingly be seen that by the adjustment of resistance 17, the tube no longer necessarily has the characteristics of an equi-potential cathode tube, and that conditions corresponding to those existing in a tube having 45 a directly resistance heated cathode can, in effect, be duplicated.

I claim as my invention:

1. The combination with a thermionic tube having a cathode comprising a plurality of 50 sections and a heater for the cathode, of wires connected with the different sections of the cathode, and a variable resistance connected across said wires.

2. The combination with a thermionic tube 55 having a cathode comprising two leg portions and a heater for two leg portions of the cathode, of wires connected with the different leg portions of the cathode, a variable resistance connected between said leg portions of the cathode, and a reactance between the cathode and the resistance.

3. The combination with a thermionic tube 60 having a cathode including two separate members, means including a resistance wire for heating said cathode members, a wire

leading from each of said cathode members, and a variable resistance connected across said wires.

4. In a radio circuit, a combination with 70 a thermionic tube having a cathode and a heater for the cathode, and having a plate and a grid, of a plate circuit and a grid circuit, a pair of wires leading from separate points of the cathode, one of said wires being connected to the plate and grid circuits, and a resistance connected across said wires. 75

5. A radio circuit as claimed in claim 4 characterized by the provision of a reactance in one of said wires interposed between the cathode and the resistance, said reactance being shunted by a radio frequency by-pass. 80

6. The combination with a thermionic tube having a cathode formed of two separate members, means for heating said cathode members, a wire leading from each of said cathode members, and a variable resistance connected across said wires constituting the only conductive connection between the two separate members of the cathode. 85

7. The combination with a thermionic tube, 90 a cathode comprising a pair of separated cathode members, means for heating said cathode members, a wire leading from each of said cathode members, a resistance connecting the two wires, and an impedance in 95 one of the wires.

8. In a radio circuit, the combination with a thermionic tube having a pair of cathode members therein, means for heating the cathode members, said tube having also 100 a grid and plate, of a grid circuit and a plate circuit connected with a grid and plate respectively, a wire leading from one of the cathode members connected with both the grid and plate circuits, a wire leading from the other cathode member connected with the first member through a variable resistance, and an impedance in one of the wires between the resistance and the cathode member to which it connects. 105

9. The combination with a thermionic tube having a divided cathode, an alternating current heater for the cathode, an external impedance in circuit with one of the divided portions of the cathode, and a variable resistance through which the divided portions of the cathode are connected. 110

10. The combination with a thermionic tube having a cathode, an alternating current heater for the cathode, and an external impedance in circuit with the cathode for reducing current variations resulting from the actions of the alternating current heater, and a radio frequency by-pass shunted around the impedance. 115

11. The combination with a radio tube having a pair of cathodes heated by alternating current, of a resistance connecting the two cathodes, and an impedance interposed between the resistance and one of the 120 125 130

cathodes, said impedance being shunted by a capacity for by-passing radio frequency currents.

12. The combination with a thermionic tube having a cathode consisting of a pair of electron emitting members, heating means including a resistance wire for rendering said electron emitting members active, and a variable resistance connected between said electron emitting members.

10 In testimony whereof I hereunto affix my signature.
